UNITED STATES PATENT OFFICE.

JOHN G. NICOLAY, OF WASHINGTON, DISTRICT OF COLUMBIA.

FOLDING CHAIR.

SPECIFICATION forming part of Letters Patent No. 445,190, dated January 27, 1891.

Application filed June 2, 1890. Serial No. 354,028. (No model.)

To all whom it may concern:

Be it known that I, JOHN G. NICOLAY, a citizen of the United States, residing at Washington, in the District of Columbia, have invented a new and useful Improvement in 5 Folding Chairs, of which the following is a specification.

In the drawings hereto annexed, Figure 1 is a perspective view, and Fig. 2 a side view, 10 of the chair when open; Fig. 3, a side view of the chair when folded, and Fig. 4 a back view of the chair when folded.

A A and B B constitute the legs of an ordinary cross-legged chair, A A being the outer 15 pair, firmly fastened together by the cross-pieces C D, and B B being the inner pair, firmly fastened together by the cross-pieces E F, the two pairs being hinged or jointed at or near the middle, so as to permit them 20 to freely to fold together. The folding together into substantially the same plane is rendered practicable by having the cross-pieces fastened to the legs against the outer sides or edges thereof, so as to permit them to come 25 together into a single plane without obstruction from the cross-pieces, which remain outside the lines or space occupied by the legs when folded.

The back of the chair is formed by the 30 standards H H, jointed at their lower ends to the outer sides and near the top of the outer pair of legs A A, while at the upper ends of

the standards H H and against their front edges is firmly fastened the cross-piece I, so that when folded backward the standards 35 also fall into the same plane occupied by the legs.

When open for use, the back is supported by the flexible cords J J, extending from the standards to the ends of the cross-piece E, 40 which is made of sufficient length to extend to points outside the space occupied by the legs and standards when folded together. The mode of fastening the flexible cords is by holes bored through the cross-piece E and 45 through the standards H H, through which holes the cords run with simple knots on the outside.

The seat G is formed by a piece of canvas or other flexible material, extending between 50 and fastened to the cross-pieces D and E.

What I claim as my invention, and desire to secure by Letters Patent, is—

The combination of the cross-legs A and B, pivoted together, the braces C, D, E, and F, secured to the outer edges thereof, the seat G, 55 secured to braces D and E, the standards H, pivoted to legs A, and cords J, secured to said standards and braces E, substantially as described.

JNO. G. NICOLAY.
